UNITED STATES PATENT OFFICE.

WILLIAM FORREST HOMMAN, OF COLORADO SPRINGS, COLORADO, ASSIGNOR
TO THE HOMMAN REGISTERING LOCK COMPANY, OF COLORADO.

SEAL-LOCK.

SPECIFICATION forming part of Letters Patent No. 628,161, dated July 4, 1899.

Application filed April 30, 1898. Serial No. 679,398. (No model.)

To all whom it may concern:

Be it known that I, WILLIAM FORREST HOMMAN, a citizen of the United States, residing at Colorado Springs, county of El Paso, 5 and State of Colorado, have invented a new and useful Improvement in Car-Locks, of which the following is a specification, reference being had to the accompanying drawings, which form a part hereof.

10 My invention relates particularly to the class of locks used on the doors of freight-cars for the purpose of protecting their contents while in transit. As is well known, such cars have frequently to be opened while in transit, 15 and it is necessary that whatever form of fastening may be employed for securing the doors should be so arranged that it may be readily opened by station agents and conductors in the employment of the railway 20 company. The devices heretofore in common use for securing the doors of such cars have usually consisted of lead seals applied to wires or metallic strips and of locks of various forms secured with clay or metallic strips so 25 arranged that the door cannot be opened without destroying the seal. Such devices at the most merely serve to show when they are left intact that the car-door has not been opened by any unauthorized person, and they are 30 open to the very serious objection of furnishing no record as to the person by whom the car is opened in the ordinary course of business. As is well known, transportation companies using devices of this type have suffered 35 heavy losses from thefts of freight by dishonest employees without being able to trace such thefts. Locks for car-doors have also been devised which were intended to indicate or record distinctive keys used by different 40 persons for opening them—such, for example, as those described in United States Patents No. 208,033 to Pershall and No. 232,069 to Russell. My present invention relates to improvements upon locks of this class 45 or type; and it is the object of my invention to provide a more efficient lock for such cars which can readily be opened by any person authorized to do so, but which preserves a permanent record within the lock of the impression made by the keys used for unlocking 50 it. By this means a record may be kept in

the lock of the different employees opening the car by providing each one who is authorized to unlock it with a key producing a distinctive impression.

55

In the drawings I have shown my invention as applied to a padlock of a well-known type, in which a curved yoke-piece slides longitudinally in a recess in the body of the padlock and is adapted to be passed through and secured in the staple or other fastening to which it is to be applied. It is obvious, however, that the invention may be readily applied by suitable modification of the parts to any other form of padlock or to a lock having a sliding bolt, and, in fact, the sliding yoke-piece in the lock which I have shown corresponds in function and substantially in construction to the sliding bolt of an ordinary lock.

70

Figure 1 is a plan view of a padlock constructed according to my invention with the cover and a portion of the internal parts removed. Fig. 2 is a plan view of part of the casing of the lock. Fig. 3 is a view of the cover. Fig. 4 is a plan view of the rotating disk carrying the blanks or seals. Fig. 5 is a longitudinal section of the lock through the line 1 2 of Figs. 1, 2, and 3. Fig. 6 is a cross-section of the same on the line 3 4 of Figs. 2, 3, and 4. Figs. 7 and 8 are detached views of the blanks or seals used with the disk of Fig. 4, and Figs. 9, 10, and 11 are views of the key or unlocking device.

75

The same letters of reference indicate like parts in each view.

The body of the lock consists of a back piece A and a front piece A', which together inclose and support the working parts of the lock.

90

B is a curved yoke-piece sliding longitudinally in a recess formed in the parts A A'. The part of the yoke at the left extends downward into a recess formed in the parts just mentioned; but at the right the yoke is shortened, so that when it is drawn out of the recess the end at the right may be slipped through a staple or other fastening, and when the yoke-piece is moved downward and the end at the right is brought in contact with the body of the lock, as shown in Fig. 1, the lock is secured in the staple. The extension

95

100

B' of the yoke-piece carries at its lower end the pawl P, which engages with the teeth of a ratchet R. The ratchet is mounted upon a short shaft S, Fig. 5, and carries on its upper side an extension C, which passes through an opening in the upper part of the framework A'. The part of this extension passing through the framework A' is cylindrical in shape and constitutes an upper bearing for the ratchet; but the upper end is square. A 50 detent D serves to prevent the ratchet from turning backward. As will be observed, the arrangement of the parts is such that when the yoke-piece B is drawn outward upon opening the lock the ratchet R is rotated, and when the yoke-piece is pushed inward for locking the pawl P slips back and engages with another tooth of the ratchet, so that upon opening the lock again the ratchet will 55 be turned another tooth. The part A' of the body of the lock, as shown in Fig. 2, is provided on its upper surface with an annular recess E for receiving the blanks or seals carried by the seal-disk F. (Best shown in Fig. 4.) This disk is provided with a square opening in the center, which fits over the square end of the extension C of the ratchet, so that the disk is turned with the ratchet. This disk, as shown in Fig. 4, is provided with a 60 series of recesses g about its periphery, and in these recesses are fitted blanks of some material—such, for example, as lead—which, although plastic or compressible, has considerable strength. The recesses have their 65 edges convex to engage with grooves in the sides of the blanks. These blanks are made, as shown in Fig. 8, with their bodies of substantially the same thickness with the disk F, but with projections p on their lower sides 70 of substantially the same depth as the annular recess E in the plate A'.

In the lower part of the annular recesses E is a lug or stop L, extending upward, so as to just clear the body of the disk F and to lie in the path of movement of the projections p of the blanks g, carried by the disk. It will be obvious that when the blanks g are in place the projections p will be arrested by the lug L, and this will prevent the disk and the 75 ratchet connected with it from rotating. With the parts in this position when the yoke-piece B is pushed inward for locking it cannot be pulled outward again until the projection p on the blank in the disk F which happens to 80 be in contact with the lug L is removed or thrown out of engagement with the lug. For the purpose of throwing such projections p out of engagement with the lug for opening the lock a keyhole K is provided in the lower 85 part of the body of the lock, through which a key or other suitable unlocking device may be passed for compressing the projection into a plane substantially coinciding with the lower plane of the disk carrying the blanks. 90 A suitable form of key or unlocking device is shown in Figs. 9, 10, and 11. The part N, forming the key proper, is provided with a

face M, which may be brought up against the lower face p of the seal in contact with the lug L and used to compress the projection by 95 driving it back into the recess sufficiently to enable it to clear the lug. In practice I find it convenient to make the unlocking device in the form of a pair of pliers, as shown in Fig. 9, of which the key proper, N, with its 100 extension O, forms one side. The other side Q R consists of a plain jaw Q and a handle R, corresponding to the handle O. The jaw Q serves as a fulcrum for bearing against the casing of the lock and enabling the key proper 105 to be pressed against the under side of the seal g with sufficient force to compress it to the requisite extent. Fig. 10 is a view of the under side of the pliers, showing the key proper, N, at the left, and Fig. 11 is a view of 110 the upper side of the key proper. The key and the part of the lock in which it is inserted may be constructed in any of the ways understood in the art so as to make it necessary to use a distinctive key for each lock. 115 The face of the key or unlocking device is provided with some distinctive figure or symbol, as is shown at I in Fig. 11, so that when it is used for compressing the blank it leaves a seal or impression on the blank corresponding to such symbol or device. In practice 120 each employee of a transportation company who is authorized to open a car will be provided with a key having some distinctive symbol, so that whenever he uses it for the purpose of opening the lock he must necessarily leave an impression corresponding to his key upon the blank which is compressed by it. 125

After the lock has once been opened in the manner described it is obvious that it may be 130 locked again by merely pushing in the yoke-piece B and that the next blank g, carried by the disk F, will then come in contact with the lug L and again dog the lock, and to open it again the next blank in order will be compressed in the same manner, and the impression of the key used for producing this result will be left on such blank. In this manner 135 a mere inspection of the disk F will show at any time what keys have been used for opening the car and in what succession.

To enable the disk F to be taken out of the lock for inspection or for refitting with blanks, the cover O, (best shown in Fig. 3,) which protects it, is made removable. It is, as shown 140 in Fig. 6, inserted in dovetail grooves in the casing A', so that it may be readily slipped out, but is normally locked in place by a pin Q, fitted in a recess q in the plate. This pin is provided with any suitable form of lock, so 145 that it cannot be opened except with a key kept only by inspectors or other persons authorized to open the seal-box of the lock.

It will be observed that the compressible blanks carried by the disk F correspond in 150 function to the dog or detent which serves in the ordinary lock to lock or dog the sliding bolt or other movable part against unlocking. So far as I am aware the use of

plastic or compressible material for such dog or detent is novel with me. It is obvious that any desired number of the plastic or compressible blanks may be used in the lock.

5 For some purposes, where a lock is to be opened only once, the advantages of my invention may be secured by the use of only a single blank.

In order to prevent the removal of the key
10 until the lock is closed, an arrangement of
levers and dogs is provided, as shown in the
lower part of Fig. 1, for locking the key in
the keyhole when it is inserted and releasing
it when the yoke is pushed in for closing the
15 lock. The lever *a* is arranged so that its outer
end (at the left) is in the path of movement of
the key, and it is normally pressed downward
by the spring shown at the right. As an ad-
ditional safeguard against opening the lock
20 when the parts are in their normal position,
a lug *b* on the lever *a* is arranged to dog the
detent *D* and so lock the ratchet *R* when the
lever *a* is not lifted by the key. A short up-
right lever *c*, carried by the lever *a*, impinges
25 on the end of the yoke *d*, carried by the lever
e, as the lever *a* is carried upward by the in-
sertion of the key and swings the left-hand
end of the yoke downward until it falls into
the notch in the pawl *P*, which allows the
30 spring applied to the lower end of the lever *e*
to swing it to the right. A lug or hook *f* on
the lower end of the lever *e* is by this means
forced into a notch in the key (shown at *J* in
Figs. 10 and 11) and locks it in place. As
35 the lever *a* moves upward the lug *b* swings
past the heel of the detent *D*, and when the
key has been used to compress the blank seal
engaging with the lug *L* the yoke is free to
be drawn out and the lock may be opened.
40 The key is, however, still held in the lock by
the hook on the lever *e* until the yoke is
pushed in again in closing the lock, when the
pawl *P* slips into a tooth in the ratchet and,
striking the left-hand end of the yoke *d*, drives
45 the upper end of the lever *e* to the right and
releases the lug or hook on its lower end from
the notch in the key.

It is obvious that my invention is not con-
fined to the form of lock nor to the precise de-
50 tails of construction which I have shown, as
the same principles of construction and oper-

ation may be applied to other forms of lock
and the details of construction may be greatly
varied.

What I claim as new, and desire to secure 55
by Letters Patent, is—

1. The combination in a lock of a movable
yoke-piece or bolt, a dog or detent controlling
the yoke-piece or bolt, and a stop in the line
of movement of the dog or detent, the said dog 60
or detent being constructed of plastic or com-
pressible material so that it may be thrown
out of engagement with the stop by compress-
ing it with a key or unlocking device, sub-
stantially as described. 65

2. The combination in a lock of a movable
yoke-piece or bolt, a plate connected to and
moved by the yoke or bolt on its unlocking
movement, one or more dogs or detents car-
ried by the plate, and a stop or lug in the line 70
of movement of the dogs or detents, each of
the said dogs or detents being made of plastic
or compressible material and adapted to be
thrown out of engagement with the stop by
compression with a suitable key or unlocking 75
device, substantially as described.

3. The combination in a lock of a movable
yoke or bolt, a ratchet actuated by the yoke
or bolt on its unlocking movement, a disk
carried by the ratchet, a series of dogs or de-
tents arranged on the periphery of the disk 80
and a stop adapted to engage with the dogs
or detents, each of the dogs or detents being
constructed of plastic or compressible mate-
rial and adapted to be thrown out of engage- 85
ment with the stop by compression with a
suitable key or unlocking device, substan-
tially as described.

4. The combination in a lock of a movable
yoke or bolt, one or more dogs or detents of 90
plastic or compressible material controlling
the yoke or bolt, a stop for such dogs or de-
tents, a key for compressing the dogs or de-
tents so as to throw them out of engagement
with the stop, and means for locking the key 95
in the lock when it is inserted and releasing
it when the lock is again closed, substantially
as described.
